A. C. SMITH.
 COMBINATION TOOL.
 APPLICATION FILED JUNE 10, 1905.

UNITED STATES PATENT OFFICE.

ALFRED C. SMITH, OF DOBBS FERRY, NEW YORK.

COMBINATION-TOOL.

No. 802,384.

Specification of Letters Patent.

Patented Oct. 17, 1905.

Application filed June 10, 1905. Serial No. 264,683.

To all whom it may concern:

Be it known that I, ALFRED C. SMITH, a citizen of the United States of America, residing at Dobbs Ferry, in the county of Westchester 5 and State of New York, have invented new and useful Improvements in Combination-Tools, of which the following is a specification.

This invention relates to combination-tools, 10 and has for its object to provide a simple, convenient, powerful, durable, and efficient tool of this character which is adapted to be used as a screw-jack, plain vise, or pipe-vise at will.

The preferred embodiment of the invention 15 is illustrated in the accompanying drawings, in which—

Figure 1 is a view in elevation of one side of the device. Fig. 2 is a similar view of the opposite side of the device. Fig. 3 is a central 20 vertical section. Fig. 4 is an end elevation. Fig. 5 is a top plan view.

Referring now more particularly to the drawings, the numeral 1 represents an inverted-yoke-shaped frame comprising vertical 25 parallel standards 2, connected at their upper ends by a cross-piece 3 and at their lower ends by a base-plate 4, which latter is provided with openings 5 for the passage of suitable fastenings to secure the device to a floor or 30 other suitable fixed support.

Integral with the cross-piece 3 is a guide-sleeve 6, provided with a vertical slot 7 at one side thereof, and arranged below said sleeve 6 is another guide-sleeve 8, carried by a cross 35 bar or piece 9, supported by the standards 2. Mounted for vertical movement in these guide-sleeves 6 and 8 is a screw shaft or shank 10, provided at its upper end with a lifting-head 11 and carrying a lug or pin 12, projecting 40 into the slot 7, whereby said shank or shaft is held from rotary movement, but is permitted to slide freely in a vertical plane through the two sleeves 6 and 8. The sleeve 6 is provided at one side with a stationary jaw 13, adapted 45 to coöperate with a movable jaw 14, carried by the head 11.

Supported by the sleeve 8 and engaging said shaft between the cross-bars 3 and 9 is an operating-nut 15, whose threads are properly 50 formed to engage the threads of the shaft. Above this nut is a swiveled collar 16, which bears upon the upper edge of the nut. An operating-lever 17 is pivoted to this swiveled 55 collar, is indicated at 18, and carries a dog 19 to engage receiving teeth or recesses 20, formed in the periphery of the nut. When the dog

is in locking engagement with one of the recesses, the nut may be turned in either direction by swinging the lever in a horizontal plane, and by successive adjustments of the lever to engage different recesses the nut may be intermittently rotated to move the shaft 10 up or down, thus adjusting the head 11 and jaw 14 toward and from the guide-sleeve 6 and jaw 13. By this means the head 11 is 65 adapted to be raised and lowered to serve the function of a lifting-jack and to move the jaw 14 toward and from the jaw 13 to form a plain vise for clamping various objects to be repaired or otherwise treated. In order to reduce friction and permit easy action of the nut 15, antifriction bearing-balls 21 may be interposed between the same and the collar 8 and swiveled sleeve 16.

On the base-plate 4 is a fixed jaw 22, provided with a toothed segmental recess 23, located immediately below a screw-shaft 10. This jaw 22 is adapted to receive pipes, bars, and other cylindrical objects which cannot be firmly clamped between the jaws 13 and 14. 80 The pipe or other object to be held is forced into engagement with the jaw 22 by the lower end of the screw-shaft 10, which is thus adapted to be employed as a coacting clamping-jaw.

From the foregoing description the construction and mode of operation of the device will be readily understood, and it will be seen that it provides a combination-tool which is designed to serve the triple function of a wagon or other vehicle-jack, a plain vise, and 90 a pipe-vise, and may be used for either purpose at will, thus producing a tool which may be conveniently employed in wagon and carriage repositories, automobile-garages, and other similar establishments for removing the 95 wheels of vehicles for lubrication and various kinds of repair work.

Having thus described the invention, what I claim is—

1. A combination-tool of the character described, comprising a frame having upper and lower fixed jaws, a screw-shaft mounted in the frame and provided at its upper end with a lifting-head and jaw, said jaw being adapted to coöperate with the upper fixed jaw and the lower end of the screw with the lower fixed jaw to form vises, and means for operating the screw-shaft.

2. A combination-tool of the character described comprising a frame having a guide-sleeve provided with a slot therein, and carrying a fixed jaw, a shaft slidable in said sleeve

and provided with a projection movable in said slot, said shaft also being provided with a lifting-head and a jaw to coöperate with said fixed jaw, a nut supported by the frame and engaging the shaft, and means for rotating said nut.

3. A combination-tool of the character described comprising a frame having a guide-sleeve provided with a slot therein, and carrying a fixed jaw, a shaft slideable in said sleeve and provided with a projection movable in said slot, said shaft also being provided with

a lifting-head and a jaw to coöperate with said fixed jaw, a nut supported by the frame and engaging the shaft, a swiveled collar, and an operating-lever pivoted to said collar and provided with a dog to engage and turn the nut. 15

In testimony whereof I affix my signature in presence of two witnesses.

ALFRED C. SMITH.

Witnesses:

JOHN F. DONAHUE,
THOS. MAGRATH.
